J. FEIGENBAUM

INCINERATOR

Filed Nov. 30, 1923

UNITED STATES PATENT OFFICE.

JOSEPH FEIGENBAUM, OF LOS ANGELES, CALIFORNIA.

INCINERATOR.

Application filed November 30, 1923. Serial No. 677,903.

To all whom it may concern:

Be it known that I, JOSEPH FEIGENBAUM, a citizen of the United States, residing at Los Angeles, in the county of Los Angeles 5 and State of California, have invented new and useful Improvements in Incinerators, of which the following is a specification.

This invention relates to incinerators and has for an object to provide an improved 10 incinerator built of sections of reenforced concrete composition.

An object is to provide a concrete incinerator of simple and substantial construction and one in which provision is made 15 for expansion and contraction of the body or shell to secure durability and long life.

Other objects and advantages will be made manifest in the following specification of an embodiment of the invention ill- 20 lustrated in the accompanying drawings, wherein:

Fig. 1 is a perspective of an embodiment of the incinerator.

Fig. 2 is a side elevation, parts being 25 broken away.

Fig. 3 is a plan and partial sectional view.

One of the broad purposes of the present invention is to provide a domestic incinerator of such construction that the fire 30 hazard made possible by the contact of objects against the exterior of the incinerator may be materially reduced and practically overcome. The incinerator is largely if not wholly constructed of a fire-resisting ma- 35 terial with small or no exterior metal exposures likely to ignite objects brushing against the incinerator while highly heated.

The incinerator as shown includes a substantially annular concrete shell or fire-box 40 constructed of a plurality of matching segments 6, forming a frustum of a cone, such segments being provided with longitudinal matching edges. These segments are made of a fire-resisting composition, and prefer- 45 ably are of a concrete structure having reinforcing wires or fabric 7. This form of incinerator is provided with a spark-arresting screen 16^a which is preferably hingedly connected at 16^b to the open top of the in- 50 cinerator so that the screen can be readily

lifted to permit discharging the rubbish into the incinerator. This form of incinerator is adapted to be arranged with its lower end or base directly upon the ground and within the base end there is arranged a grate 55 foundation in the form of a monolith of substantially circular outline and which is adapted to be surrounded by the incinerator shell. The grate-ring 2 is provided with a suitable grate means, here shown as consisting of a number of parallel grate-bars 3, which may be imbedded in the top of a ring 2.

The shell is provided with means for enabling draught-flow and for cleaning out, 60 as shown. The shell has a draught-aperture 4 which may be closed or partially closed by suitable draught-controlling means here represented as a closure block 5.

This type of incinerator may be readily 70 manufactured at a manufacturing plant and the parts may be compactly nested for storage and shipment and can be readily installed by any one without skill on locations such as in yards or lots in built-up 75 communities or elsewhere. This incinerator is of very inexpensive form and method of construction and materials and provides a safe and simple means for the burning of domestic waste and rubbish and for the 80 purpose of burning of waste and rubbish of various institutions, particularly merchan- 85 dising houses.

Further embodiments, modifications and variations may be resorted to within the 85 spirit of the invention.

What is claimed is:

1. An incinerator comprising an annular reinforced concrete shell made in two pieces fitting together on vertical lines and open 90 at both ends, one end being adapted to rest upon the ground and the other end being adapted to receive material to be burned, a spark-arresting screen hinged in position to close the upper end, there being a draft 95 opening at the lower end and a movable block for regulating the draft opening, a monolithic grate ring fitting within the lower end and adapted to rest upon the ground and grate bars having their ends 100

embedded in the ring, the ring having a radial slot adapted to be in line with the draft opening.

2. An incinerator consisting of a shell 5 formed of two monolithic segments meeting on vertical lines and having a draft opening at the bottom and a filling opening at the top, a monolithic ring fitting within the

lower end of the shell and having a radial slot adapted to be in line with the draft ¹⁰ opening, and grate bars extending above and across the ring with their ends embedded in the ring.

In testimony whereof I have signed my name to this specification.

JOSEPH FEIGENBAUM.
